(57) **CLAIM**

I claim the ornamental design for a wringer for a cleaning implement, as shown and described.

DESCRIPTION

FIG. 1 is a perspective view of an embodiment of a wringer for a cleaning implement according to the present invention.

FIG. 2 is an enlarged perspective view of the wringer for a cleaning implement of FIG. 1.

FIG. 3 is a front elevational view of the wringer for a cleaning implement of FIG. 1.

FIG. 4 is a rear elevational view of the wringer for a cleaning implement of FIG. 1.

FIG. 5 is a first side elevational view of the wringer for a cleaning implement of FIG. 1.

FIG. 6 is a second side elevational view of the wringer for a cleaning implement of FIG. 1; and,

FIG. 7 is a top plan view of the wringer for a cleaning implement of FIG. 1.

The broken lines shown in the drawings are for environmental purposes only and form no part of the claimed design
